UNITED STATES PATENT OFFICE

2,603,691

MAGNETIC CORE CONSTRUCTION

Franklin R. D'Entremont, Lynnfield, Mass., assignor to General Electric Company, a corporation of New York

Application November 10, 1949, Serial No. 126,571

3 Claims. (Cl. 175—356)

1

This invention relates to stationary electrical induction apparatus, and more particularly to an improved magnetic core construction for such apparatus.

In the construction of magnetic cores for stationary electrical induction apparatus, one of the problems which is encountered is that of the magnetic saturation and core losses which occur due to the joints in the laminated material which constitutes the magnetic core.

An illustration of this problem can be found in the case of magnetic cores formed of rolled strip magnetic material such as silicon strip steel. It is conventional to form such cores of a plurality of strips of the desired magnetic material which are bent to give the required core configuration. Such a core is generally in the form of a closed loop having a hollow center, with the respective ends of each of the constituent laminated strips being jointed in order to form the closed loop. Unless the ends of the respective magnetic strips forming the core are perfectly butt jointed, which is unlikely, it can be demonstrated that the flux density in the joint section of the core will be considerably higher than in other sections of the core, since the joints in effect decrease the cross-sectional area of the core wherever they occur. This increased flux density is, of course, undesirable since it causes increased core losses and other undesirable effects.

The ideal condition would be to have no joints in the magnetic circuit at all, and the next best condition would be to have the joints completely staggered and distributed around the magnetic circuit. As neither of the aforementioned conditions can be obtained with a reasonable manufacturing cost, any construction that will approach the results that could be obtained under the ideal conditions should be of considerable value.

Accordingly, it is an object of this invention to provide a new and improved joint construction for magnetic cores.

It is a further object of this invention to provide a joint construction for magnetic cores which will provide improved magnetic and mechanical characteristics.

It is a still further object of this invention to provide a magnetic core in which the joints of the laminations comprising the core are so distributed to give improved magnetic characteristics.

In accordance with these objectives, this invention provides a joint construction for a mag-

2

netic core in which a plurality of groups of joints are used, the various groups of joints being displaced from one another either transversely or longitudinally of the core, with the respective joints within each joint group being staggered with respect to one another in accordance with the same or a similar predetermined pattern.

The features of this invention which I believe to be novel are set forth with particularity in 10 the appended claims. My invention itself, however, both as to its organization and use, together with further objects and advantages thereof, may best be understood by reference to the following description taken in connection with the accompanying drawings, in which Fig. 1 represents a 15 view in perspective of a magnetic core formed of magnetic strip material, having joints in accordance with my invention; and in which Fig. 2 represents a magnetic core constructed of flat 20 punchings and having a joint arrangement in accordance with my invention.

Referring now to Fig. 1, there is shown a laminated magnetic core 1, which is formed of a plurality of strips 2 of some suitable rolled magnetic 25 material, such as silicon steel. Knowing the inner and outer peripheral distances of the core and the thickness of the core, the strips 2 may be precut into the lengths necessary to form the joint pattern to be described hereinafter. They 30 may be cut either by hand or on a suitable index shearing machine. These precut strips may then be assembled and expanded into a desired core configuration in accordance with any suitable methods such as, for example, those described in Patent 2,456,457—Somerville, which 35 is assigned to the same assignee as the present application.

In accordance with my invention, I have divided the laminated layers of the magnetic core 40 1 into a plurality of groups for jointing purposes. In the embodiment illustrated in the drawing, I have used four laminated layer groups, with each group being composed of four consecutive laminations. However, it will be understood that I 45 may use a different number of layer groups with a different number of layers per group.

Thus, layer group I is comprised of layers numbered 3, 4, 5, and 6; group II is comprised of layers 7, 8, 9, and 10; group III is comprised of layers 11, 12, 13, and 14; and group IV is comprised of layers 15, 16, 17, and 18.

An inspection of the joint pattern in the core shown in the drawing reveals that each complete oblong lamination layer is comprised of an upper inverted U-shaped lamination, and a low-

er U-shaped lamination, with the respective leg members for each layer meeting in a joint on both the left-hand and right-hand core legs. That is, each laminar layer is jointed in two places, one joint being in the left-hand core leg, as viewed in the drawing, and the other joint being in the right-hand core leg.

In order to obtain a joint pattern in accordance with my invention, I provide alternate groups of long and short upper inverted U-shaped laminations, with corresponding short and long lower U-shaped laminations. That is, the laminar layers 3, 4, 5 and 6 of the group and layers 11, 12, 13, and 14 of group III are formed by joining long upper inverted U-shaped strip members to short lower U-shaped strip members. Similarly, the layers 7, 8, 9, and 10 of group II and 15, 16, 17, and 18 of group IV are formed by joining short upper inverted U-shaped strips to long lower U-shaped strips. Thus, I have built up the core by alternately stacking groups of long and short upper laminations, with the corresponding groups of lower laminations being short and long.

Due to lengths of the upper and lower members of the various laminated layers, as just described, the joints in layer groups II and IV are located in the upper end of the core, as viewed in the drawing, while the joints in layer groups I and III are located in the lower part of the core. While the joints of both layer groups II and IV are located in the upper end of the core, yet these two groups of joints are offset from each other transversely of the core due to the intervening layers of group III. Likewise, the joints for layer groups I and III in the lower part of the core are offset from each other transversely of the core due to the intervening layers of group II.

Furthermore, in accordance with my invention, the joints within each group are staggered with respect to one another so that adjacent layer joints within a given group are displaced from one another lengthwise of the core a relatively much greater amount than the joint displacement of alternate layers. It will be seen that the laminations within each group differ in length from one another, with an appreciably greater length differential between adjacent laminations than between alternate laminations.

Thus, considering, for example, the lamination layers of group I in the left-hand core leg, it will be seen that while the laminated layers 3, 4, 5, and 6 of group I are as a group all comprised of upper inverted U-shaped members having long left legs and lower U-shaped members having short left legs, yet the legs of the upper members for layers 3 and 5 are considerably longer than the corresponding legs for the upper members of layers 4 and 6.

Conversely, in the right-hand core leg, the legs of the upper U-shaped members composing layers 3 and 5 are shorter than the corresponding legs of the upper members for layers 4 and 6.

In order to improve the mechanical strength and characteristics of the core, the left-hand and right-hand legs of each of the inverted upper U-shaped members and lower U-shaped members are made of unequal length in the manner just described for the layers of group I. While both legs of each U-shaped member are always in the same length category, i. e., long or short, yet there is always a differential in length between the legs for the right- and left-hand leg members.

In accordance with my invention, the lengths

of the upper and lower U-shaped laminar strips are arranged so that the lower and upper joints, respectively, of joint groups in the same region of the core are progressively stepped in the same direction in such manner as to lie along the same oblique line transverse of the core. Thus, for example, joints for layers 3 and 5 of group I and joints for layers 11 and 13 of group III are progressively stepped downwardly these four joints defining an oblique line D—D which is directed slightly downwardly toward the outer edge of the core. Similarly, joints for layers 4, 6, 12, and 14 of groups I and III define an oblique line C—C which is parallel to, but higher than, the line D—D defined by joints for layers 3, 5, 11, and 13.

At the upper end of the core leg, joints for layers 8, 10, 16, and 18 of joint groups II and IV, are progressively stepped upwardly to define an oblique line B—B which is directed upwardly toward the outer edge of the core leg. Also, joints for layers 7, 9, 15, and 17 of joint groups II and IV are progressively stepped upwardly to define an oblique line A—A which is parallel, but above, the line B—B defined by the joints for layers 8, 10, 16, and 18.

The effect of the length differential between the opposite legs of each of the U-shaped laminar members as previously mentioned is best shown by the juxtaposition in the relation between lines A—A, A'—A' and B—B, B'—B' and between C—C, C'—C' and D—D, D'—D', which are defined by the joint patterns on the two core legs. Thus, while lines A—A and A'—A' are defined by joints for layers 7, 9, 15, and 17 in the left-hand and right-hand core legs respectively, and lines B—B and B'—B' are defined by joints for layers 8, 10, 16, and 18 in the left-hand and right-hand core legs, respectively, it will be noted that line A—A is higher than line B—B in the left-hand core leg but that line A'—A' is lower than line B'—B' in the right-hand core leg. Similarly, line C—C, defined by joints for layers 4, 6, 12, and 14 is higher than line D—D, defined by joints for layers 3, 5, 11, and 13 in the left-hand core leg, but line C'—C' is lower than line D'—D' in the right-hand core leg.

There is shown in Fig. 2 an embodiment of my invention as applied to a magnetic core constructed of flat punchings. The magnetic core shown in Fig. 2 is constructed of a plurality of layers of flat punched U-shaped laminations assembled to form a magnetic core of generally hollow rectangular shape. Each laminated layer comprises two U-shaped punchings having their respective leg members placed end to end in a butt joint to form a closed loop. Each laminated layer has one U-shaped punching with short legs which mates with a U-shaped punching having long legs.

In accordance with my invention I stack alternate groups of long- and short-legged U-shaped punchings at a given end of the magnetic core so that adjacent groups of laminated layers have their respective joints at opposite ends of the core. Furthermore, within each group of laminated layers I have staggered the joint arrangement so that joints within a given group are offset from one another.

Referring now to Fig. 2, it will be seen that the four topmost layers 19, 20, 21, and 22 have long U-shaped punchings with legs which extend well into the lower part of the core legs. Thus, the joints for layers 19, 20, 21, and 22 are all in the lower part of the core with respect to the view shown in the drawing. However, the sec-

ond group of laminated layers including layers 23, 24, 25, and 26 have the respective legs of the upper and lower U-shaped punchings of such length that the joints between the upper and lower punchings are in the upper portion of the core with respect to the view shown in the drawing. The third group of layers including layers 27, 28, 29, and 30 are positioned in the lower part of the core and the fourth group of layers including layers 31, 32, 33, and 34 have their joints positioned in the upper portion of the core with respect to the view shown in the drawing. Thus, it will be seen that in accordance with my invention I position the joints for a group of adjacent laminar layers at one end of the core leg with the adjacent group of laminar layers being jointed at the opposite end of the same core leg. Furthermore, I stagger the joints within each group so that the joints within a given group are offset from one another, although all joints in a given group are in the same general region of the core leg. Thus, the joints in layers 19, 20, 21, and 22, while all in the lower region of the core leg, with respect to the view shown in the drawing, are offset from one another in such manner as to define two lines C—C' and D—D' extending transversely and obliquely across the core leg. Similarly, the joints for layers 27, 28, 29, and 30, which are also in the lower region of the core, are staggered from one another, and I prefer to so position these joints as to lie along the same lines C—C' and D—D'. In the upper part of the core, with respect to the view shown in the drawing, the joints for layers 23, 24, 25, and 26 are offset from one another in such manner as to define the lines E—E' and F—F' extending transversely and obliquely across the core leg, and similarly the joints for layers 31, 32, 33, and 34 are offset from one another, and I prefer to so position these joints that they also lie along the lines E—E' and F—F'.

In the opposite core leg, U-shaped punchings are in the same length category as in the leg just described. That is, U-shaped punchings which are short in one leg are also short in the other core leg. However, I prefer to reverse the offset relation within each group of adjacent laminations in such manner that the joints which are on line C—C' in the left core leg will fall along line C—C' in the right core leg, and the joints for layers which are jointed along line D—D' in the left core leg will be jointed along line D—D' in the right core leg. Similarly, joints for layers which are jointed along line E—E' in the left core leg are preferably jointed along E—E' in the right core leg, and layers which are jointed along line F—F' in the left core leg are preferably jointed along the line F—F' in the right core leg.

It can be seen that I have provided a plurality of groups of joints for the laminations comprising the core of a stationary electrical induction apparatus, with each of the groups being displaced from the others either transversely or longitudinally of the core, and with the component laminations making up each of the groups having their joints staggered or stepped with relation to each other. By this means, I maintain practically uniform flux density throughout the core despite the joints, in contrast to the greatly increased flux density which would be experienced if all of the joints were concentrated in the same core cross-sectional area.

While I have shown in my drawing and description a core having only four joint groups,

with each group having four laminations, it is obvious that a greater number of groups could be used, and that a greater number of laminations could be used in each group, either increasing the number of steps or the number of laminations per step. It is also obvious that wherever I have shown or described a single layer of laminated magnetic material, such a single layer may represent a plurality of laminated layers.

While there have been shown and described particular embodiments of my invention, it will be obvious to those skilled in the art that various changes and modifications can be made therein without departing from the invention, and, therefore, it is aimed in the appended claims to cover all such changes and modifications as fall within the true spirit and scope of the invention.

What I claim as new and desire to secure by Letters Patent of the United States is:

1. A magnetic core for stationary electrical induction apparatus comprising a plurality of layers of magnetic material, said plurality of layers of magnetic material comprising a plurality of superposed layer groups of laminated magnetic material each of said layers forming a closed loop having a hollow center, each of said layers being formed of two U-shaped magnetic members having their respective leg members joined end-to-end in a butt joint to form said closed loop, the joined leg members of said U-shaped members constituting the legs of said magnetic core, the joints for said plurality of layers being disposed in a plurality of groups along the respective legs of said magnetic core to reduce magnetic saturation in the joint areas, each layer group in a given core leg having a joint group corresponding thereto, joint groups for adjacent groups of laminated layers lying in a given core leg being positioned at opposite ends of that core leg, joint groups for alternate groups of laminated layers lying in a given core leg being positioned at the same end of that core leg, and a staggered arrangement within each joint group so that joints for even-numbered layers within each layer group are progressively offset in the same direction and define a line running obliquely of the thickness of said layers of magnetic material, the joints for odd-numbered layers within each layer group being progressively offset in the same direction as the joints of said even-numbered layers, and also defining a line running obliquely of the thickness of said layers, the respective lines defined by the joints of said even- and odd-numbered layers of each joint group being substantially parallel to each other but displaced from each other by a substantially greater distance than the distance separating adjacent joints lying on a given oblique line, the two oblique lines defined by each joint group at an end of a given core leg being substantially co-linear with the two oblique lines defined by the other joint groups at said end of said core leg.
2. A magnetic core for stationary electrical induction apparatus comprising a plurality of layers of magnetic material, said plurality of layers of magnetic material comprising a plurality of alternate groups of long U-shaped laminations in superposed relation with alternate groups of short U-shaped laminations so that adjacent groups of said laminations are of opposite length, each of said layers forming a closed loop having a hollow center, each of said

layers being formed of two U-shaped magnetic laminations having their respective leg members joined end-to-end in a butt joint to form said closed loop, the joined leg members of said U-shaped laminations constituting the legs of said magnetic core, said core being formed by stacking alternate groups of long and short U-shaped laminations mating with corresponding groups of short and long U-shaped laminations, to thereby cause joints for adjacent groups of laminations lying in a given core leg to be positioned at opposite ends of that core leg and joints for alternate groups of laminations lying in a given core leg to be positioned at the same end of that core leg, and a staggered arrangement within each group so that joints for even-numbered layers within each group are progressively offset in the same direction and define a line running obliquely of the thickness of said layers, the joints for odd-numbered layers within each group being progressively offset in the same direction as the joints of said even-numbered layers, and also defining a line running obliquely of the thickness of said layers, the respective lines defined by the joints of the even- and odd-numbered layers within a given group being substantially parallel to each other but displaced from each other by a substantially greater distance than the distance separating any two adjacent joints lying on a given oblique line within that group, the two oblique lines defined by each group at an end of a given core leg being substantially co-linear with the two oblique lines defined by the joints of the other groups at said end of said core leg.

3. A magnetic core for stationary electrical induction apparatus comprising a plurality of layers of magnetic material, said plurality of layers of magnetic material comprising a plurality of alternate groups of long U-shaped laminations in superposed relation with alternate groups of short U-shaped laminations so that adjacent groups of said laminations are of opposite length, each of said layers forming a closed loop having a hollow center, each of said layers being formed of two U-shaped magnetic laminations having their respective leg members joined end-to-end in a butt joint to form said closed loop, the joined leg members of said U-

shaped laminations constituting the legs of said magnetic core, said core being formed by stacking alternate groups of long and short U-shaped laminations mating with corresponding groups of short and long U-shaped laminations, the opposite legs of each of said U-shaped laminations being of unequal length but yet at the corresponding ends of the respective core legs in which they are positioned, joints for adjacent groups of laminations lying in a given core leg being positioned at opposite ends of that core leg, joints for alternate groups of laminations lying in a given core leg being positioned at the same end of that core leg, and a staggered arrangement within each group so that joints for even-numbered layers within each group are progressively offset in the same direction and define a line running obliquely of the thickness of said layers of magnetic material, the joints for odd-numbered layers within each group being progressively offset in the same direction as joints of said even-numbered layers and also defining a line running obliquely of the thickness of said layers, the respective lines defined by the joints of said even- and odd-numbered layers within a given group being substantially parallel to each other but displaced from each other by a substantially greater distance than the distance separating any two adjacent joints lying on a given oblique line within that group, the two oblique lines defined by each group at an end of a given core leg being substantially co-linear with the two oblique lines defined by the joints of the other groups at said end of said core leg.
